UNITED STATES PATENT OFFICE.

DAVID N. LAMBERT, OF BROOKLYN, NEW YORK.

GAS-METER-PROTECTION MEANS.

Application filed August 26, 1925. Serial No. 52,646.

To all whom it may concern:

Be it known that I, DAVID N. LAMBERT, a citizen of the United States, residing at Brooklyn, in the county of Kings and State 5 of New York, have invented new and useful Improvements in Gas-Meter-Protection Means, of which the following is a specification.

This invention relates to gas meter protecting means, and the primary object of the same is to provide simple and effective devices in connection with a portion of the meter to prevent any possibility of tampering with the valves or vulnerable parts of 10 the meter by unauthorized persons and thereby obstruct nefarious interference with the regular flow of gas through the meter and false registration of the amount of gas used by a consumer.

20 The essential feature of the invention is to introduce baffle means in the gas forked channels leading from one of the pipes into the meter and having a slide valve cooperating with each fork, the improvement broadly consisting in disposing an occluding or baffle means at the juncture of the forks to prevent insertion of a wire or analogous device to lift either of the valves 25 from its seat and permit outflow of the gas for service purposes, to defeat the regular 30 registration of the amount of gas used.

In the drawings a preferred construction 35 of the improved occluding or baffle means associated with the forks or forked channels is illustrated as well as the modification of the ducts adjacent to their point of juncture to render the improved occluding feature more effective in its operation. It will be understood in this connection that changes 40 involving equivalent structures within the scope of the present invention are intended to be adopted and that the form of the occluding or baffle means shown as well as the modification of the shape of the ordinary 45 forks adjacent to their point of juncture may be varied without departing from the spirit of the invention.

In the drawings:

Fig. 1 is a longitudinal vertical section 50 of the upper portion of the ordinary form of gas meter showing the improved structure applied thereto and also shown in section.

Fig. 2 is a bottom plan view of the upper 55 valve chamber of the meter, showing the forked ducts or channels with the improved

occluding or baffle means shown in dotted lines therein.

Fig. 3 is a detail front elevation of the forked ducts or channels, showing the improved baffle means therein.

Fig. 4 is a side elevation of the improved forked structure, showing the offset structure to render the occluding or baffle means therein more effective.

Fig. 5 is a top plan view of the forked duct or channel means and the improved occluding or baffle device disposed therein.

The numeral 5 designates the casing or enclosure of the well known form of gas meter having the lower diaphragm structure 6 of the usual type and operating in a manner well understood, and an upper valve chamber 7, at opposite ends of which are inlet and outlet pipes 8 and 9, the inlet pipe being continued under the valve chamber by means of a straight duct 10, which has an upper port or opening 11, to admit gas into the chamber 7. This chamber 7 has oppositely disposed slide valve organizations 12 70 cooperating with ports 13 and 14 arranged in pairs in connection with each valve 12. The valves 12 are reciprocated on their seats 15 by crank mechanism 16 operated through intermediate mechanism by the diaphragms 85 below and also having intermediate mechanism as at 17 which control the registration of the amount of gas used by means of the usual and well known form of dials. Channels 18 also establish communication between the diaphragms and valve chamber so that gas may enter the diaphragms in the usual manner and a part of the ports, or the outer ports 14 controlled by the valves 12 together with the lower portion of the casing exterior of the diaphragms, for well known purposes. In this type of meter the valves 12 alternately reciprocate in opposite directions and respectively open and close the ports 13 and 14 in alternation. As shown by Fig. 2, the lower side of the valve chamber 7 has a covering or enclosure 19, through which the channels 18 open, the outer ports 14 being exterior of this enclosure or cover. The valve seats 15 also have intermediate ports 20, as shown by dotted lines in Fig. 2, which communicate with the inner extremities of the forks 21 leading from the oppositely disposed, alternately operating valves to the outlet pipe or member 9.

The foregoing structure is well known in

the art and the operation thereof readily understood and need not be further explained.

The improved features of the invention 5 consist in providing the usual forks or channels 21 at their point of juncture as ordinarily constructed of greater dimensions for increasing the size of of the juncture chamber 22 by forming outwardly projecting 10 offsets 23 as a part of the forked channels and then converging the walls 24 towards the point where the outlet pipe or tube 9 has its lower open extremity 9^a applied to the end of the meter casing, the application 15 of this varied form of the chamber 22 at the juncture of the forked channels or ducts 21 being clearly illustrated by Figs. 2 and 5. By forming the offsets 23 the forked channels 20 are positioned farther inward, as it were, for the purpose of structurally cooperating with an occluding or baffle means 25 consisting of two outwardly converging walls or partitions in alinement with the inner walls of the channel forks 21, the 25 walls or partitions 25 extending outwardly in divergent directions far enough over the forked channels in rear thereof to prevent the insertion of a wire or other analogous device into the said channels. The walls or 30 partitions 25 have their outer free ends bent at inward angles to form guards 26, which will serve as catching or retaining means and prevent movement of a wire that may be inserted into the outlet pipe or tube for 35 the purpose of passing into the forked channels. The walls or partitions 25 with the offsets 23 also produce shielded passages 27, to render the insertion of a wire or analogous device into the forked channels more 40 difficult. The occluding or baffle means or walls or partitions 25 and the other features of construction just specified do not in the least interfere with the free outflow of the 45 gas into the outlet pipe or tube 9 under normal conditions.

In the type of meter shown and embodying slide valves alternately operating to regulate the ports as hereinbefore noted, it is obvious that sufficient play of the valves 50 is necessary to give them a sliding action, but when these valves are in engagement with their seats, they are non-leakable and all gas passing into and out through the outlet pipe or tube 9 will have been registered as to its quantity or cubic measurement.

Many methods have been devised to defeat the regular working operation of the mechanism of meters embodying the usual 60 form of unobstructed forks or forked channels between the valve chamber and the outlet, but the principal method is to insert a wire through the outlet and under either one of the valves and slightly raise the latter 65 from its seat, to permit the gas to flow out

without registration as to quantity. It will be understood that the ports 20 communicating with the forked channels or ducts 21 allow the passage of gas that has been properly measured into the said forked channel or ducts, and the use of the forked channels or ducts and alternately operating valves results in a regular outflow of the gas without pulsation, or the gas enters the outlet pipe or tube 9 in regular flowing quantity. 70 It will be seen that the occluding or baffle means comprising the outwardly converging walls or partitions 25 are disposed in such manner that the angle of juncture of these walls or partitions is directly opposite the lower open end or portion of the pipe or tube communicating with the forks or with the chamber 22 of the latter, and the said walls or partitions will always be long enough to obstruct movement of a wire into 75 either forked channel or duct. The angular passages 27 will also serve as an obstruction even though the end of the wire inserted may be turned in such manner as to pass the outer guards 26 of the walls or partitions 25, and under the latter conditions the end of the wire will strike against the offset wall 23 and be obstructed in its movement into either forked channel or duct. 80

The improved device is exceptionally simple in its structure and may be easily applied to meters now in use at a minimum expense as well as in the primary construction of meters. 95

What is claimed as new is:

1. In a protection means for a meter of the class specified, the combination with valves, diaphragm means and a tubular conduit, of forked channels, between the tubular conduit and the valves, formed with an outer juncture chamber and baffle means continuing from the inner walls of the channels at the outer junctional portion of the said channels to prevent insertion of means into the tubular conduit and displacement of either of the valves, the said baffle means continuing into the juncture chamber a sufficient distance to obstruct direct entrance into the channels. 100

2. In a protection means for gas meters of the class specified, the combination with the usual valves, diaphragms and cooperating mechanism between the diaphragms and valves and the registering mechanism, of a pipe communicating with the interior of the meter, forked channels leading to the valves and providing communication between said valves and the pipe, and means extending completely across at a distance from the outer open portions of the forked channels for preventing insertion of a device through the pipe and channels to reach the valves for the purpose of nefariously raising the latter. 115

3. In a protection means for a gas meter 120

of the class specified, the combination with controlling valves, diaphragms and mechanism between the valves and diaphragms and registering means, of a gas flow pipe
5 having a portion thereof communicating with the interior of the meter, forked channels between the valves and the said pipe and having an enlarged juncture chamber at the outer portions thereof, said chamber
10 having angularly disposed side walls and occluding means disposed in the said juncture chamber and extending completely across and covering direct entrance into the outer open ends of the forked channels to
15 obstruct the introduction of a device into either channel for the purpose of nefariously raising either valve to permit gas to irregularly pass into the pipe.

4. In a protection means for gas meters
20 of the class specified, the combination with diaphragms, valves cooperating with the diaphragms, mechanism between the valves

and diaphragms and also cooperating with registering mechanism, of a gas outlet pipe communicating with the meter, and forked channels between the said pipe and the valves and having an outer enlarged juncture chamber with angular side walls including offsets adjacent to the point of juncture of said channels and further provided with baffle walls projecting into said chamber and continuing from the inner walls of the channels and terminating in inwardly bent angular guards at a distance from the said offsets to obstruct the introduction of a device into either of the channels for unseating the valves for the purpose of nefariously using the gas by leakage thereof through the valves into the pipe.

In testimony whereof I have hereunto set my hand.

DAVID N. LAMBERT.
